UNITED STATES PATENT OFFICE.

JOHN G. HOFFMAN, OF NEW YORK, AND GEORGE WEBER, OF BROOKLYN,
ASSIGNORS TO THE J. G. HOFFMAN MANUFACTURING COMPANY, OF
BROOKLYN, N. Y.

MECHANISM FOR OPERATING FAN-BLOWERS.

SPECIFICATION forming part of Letters Patent No. 310,681, dated January 13, 1885.

Application filed May 22, 1884. (No model.)

To all whom it may concern:

Be it known that we, JOHN G. HOFFMAN, of the city and county of New York, in the State of New York, and GEORGE WEBER, of the city of Brooklyn, in the county of Kings and State of New York, have invented a new and useful Improvement in Mechanism For Operating Fan-Blowers, of which the following is a specification.

10 Our invention relates to mechanism, which may be operated by hand, for imparting rotary motion to fan-blowers of small size, such as are commonly used for blacksmiths' forges.

In the Letters Patent granted to John R. Rowlands, No. 293,360, dated February 12, 1884, is shown and described a mechanism for rotating a large pulley, from which motion is transmitted by a belt to the fan of the blower. This mechanism consists of a rocking frame which has an oscillating or reciprocating motion imparted by a hand-lever, and which carries a drive-chain engaging with a flange or hub loose upon the pulley-shaft. Fast upon said shaft is a ratchet-wheel, and 25 the said loose flange or hub carries pawls which engage with said ratchet-wheel and impart motion to it and the pulley-shaft when said frame is swung or moved in one direction, and play idly over said ratchet-wheel when 30 the frame is swung or moved in a reverse direction. By this mechanism an intermittent impulse is imparted to the pulley, and the momentum of the pulley and fan produces an approximately uniform and continuous rotary motion.

Our invention consists in novel combinations of parts, whereby motion may be imparted to the pulley-shaft by the use of a rocking frame without the use of a chain, and 40 in other combinations of parts, whereby a hand-crank, which fits loosely upon and depends idly from the pulley-shaft when the latter is to be operated by said rocking frame, is made operative to turn the shaft by simply 45 moving it by the hand in the proper direction to turn the pulley-shaft.

These several combinations of parts are hereinafter described, and set forth in the claims.

In the accompanying drawings, Figure 1 is 50 a side elevation of a fan-blower and operating

mechanism therefor embodying our invention. Fig. 2 is an end elevation thereof. Fig. 3 is a detail sectional view of certain parts in a plane parallel with the pulley-shaft, and on a larger scale; and Figs. 4 and 5 are detail views illustrating modifications of our invention.

Similar letters of reference designate corresponding parts in the several figures.

A designates the base-plate, whereon is secured, by any suitable means, a blower, B, which may be of any suitable construction.

The upright frame for supporting the mechanism consists of two similar frames, C C, connected by cross-ties or stretchers a a'.

D designates a driving-shaft, on which is fixed a pulley, D', and from this pulley motion is transmitted by a belt, D'', to the pulley b of the fan B. The fan may be secured in such position on the base A that its pulley b, 70 on whichever side of the blower it may be, will be in line with the pulley D', or so that a blower having a pulley, b, on each side may be so placed on the base as to receive the belt D'' on one or the other of said pulleys, as may 75 be desired.

As here shown, the shaft D is mounted in bearings c, which are made separate from the side frames, C, and are adjustable in openings c* therein. Each bearing has a flange, c', and 80 is secured to its frame by a bolt, d, passing through a slot in said flange.

Upon the shaft D is securely fixed a ratchet-wheel, e, having an internally-ratchet-toothed rim, e', and between said ratchet-wheel and 85 the adjacent frame is a flange or hub, f, loosely fitting the shaft, and carrying pawls f', which engage with the ratchet-wheel e. We have here shown four pawls, f', which are simply pivoted to the flange f, and are unprovided 90 with springs. When one or more of these pawls come above the ratchet-wheel e, it falls into secure engagement therewith by gravitation, and as said pawls come below the ratchet-wheel they drop out of engagement therewith and upon stop-pins f*, which prevent them from dropping too far away from the wheel. We make no claim, broadly, to this arrangement of pawls.

On the inner side of the flange or hub f is 100

cast or securely fixed a pinion, g , and with this pinion engages a gear segment or sector, h , which forms part of a rocking frame, E , fulcrumed at i to one of the frames C .

5 In order to facilitate the smooth and noiseless running of the pinion g and gear-segment h , we form the pinion with a smooth cylindric bearing-surface, g' , at the side thereof, and the gear-segment h with a correspondingly-smooth bearing-surface, h' . These features are best shown in Fig. 3.

F designates a hand-lever fulcrumed at j to the frame E , and capable of lateral movement on a bearing surface or bracket, j' , projecting from the frame, as shown in Fig. 1. When the lever F is depressed, the segment h , acting upon the pinion g , turns the flange f in a direction to cause its pawls f' to engage the ratchet-wheel e , and so turn the shaft D and belt-pulley D' . When the lever F is raised, the flange f and pawls move in a reverse direction, and the pawls play idly over the ratchet-wheel e , the latter moving ahead by reason of the momentum of the pulley D' . 25 The return or backward movement of the frame E is assisted by a counterbalance-weight, k .

30 The pawls f' and ratchet-wheel e form a clutch-connection between the flange f and the shaft D , but, in connection with the gear on the shaft and the gear-segment on the rocking frame E , any other well-known or suitable form of clutch may be used.

35 The adjustable bearings c afford provision for adjusting the pinion g relatively to the gear-segment h , which drives it, so that the intermeshing gearing will run as noiselessly as possible; and if the bearings be made slightly flaring toward the opposite ends one or other 40 of the bearings may be adjusted to cause the pulley D' to run in a truly vertical plane.

45 In lieu of the pinion g and segment h , we may employ a gear wheel or pinion, g^* , and gear-segment h^* , having teeth of slight projection and of undulating or wavy profile, as shown in Fig. 4; or, if desired, friction-gearing may be substituted, as shown in Fig. 5. In the latter figure the pinion or gear wheel g^{**} may be covered with rubber or leather o , 50 to increase friction, and the segment friction-gear h^{**} , carried by the rocking frame E , works in tight frictional contact with said friction pinion or wheel.

55 The friction-gearing has the advantage of being noiseless in its operation; but in order to provide for the careful adjustment of the parts the friction-segment h^{**} may be connected with the rocking frame E by bolts l , as shown in Fig. 5.

60 The adjustable bearings c are particularly desirable when a friction-pinion, g^{**} , is used, as they provide for properly adjusting the pinion relatively to the segment-gear h^{**} , whether or not the latter is adjustably secured 65 to the rocking frame.

In many cases it is desirable, in addition to the rocking frame and hand-lever E F , to have a hand-crank for turning the shaft D directly by hand. To this end we provide a hand-crank, G , which depends loosely from the shaft D , so long as the mechanism is operated by the lever F , and which carries a pawl, $*$, engaging with the internally-toothed ratchet-rim e by gravity. So long as the lever F is employed as a means of operating the mechanism the crank G hangs idly, and the ratchet-teeth e' play idly under the pawl $*$ as the wheel e is turned in the direction of the arrow, Fig. 1.

When it is desired to employ the hand-crank G , all that is necessary is to grasp the crank and turn it in the direction of the arrow, Fig. 1, whereupon the pawl $*$ will remain in firm engagement with the ratchet-teeth e' , and will turn the wheel and shaft 85 continuously.

What we claim as our invention, and desire to secure by Letters Patent, is—

1. The combination, with the driving-shaft and pulley or wheel, of a gear wheel or pinion loose on said shaft, and a rocking frame provided with a segment-gear engaging with said gear wheel or pinion, a clutch-connection between said gear wheel or pinion and shaft for turning the shaft in one direction only, and 90 bearings for said shaft capable of adjustment to adapt said gear wheel or pinion to said segment-gear, substantially as herein described.

2. The combination, with the driving-shaft and its pulley or wheel, of a gear wheel or pinion loose on the shaft, a rocking frame provided with a segment-gear engaging with said wheel or pinion, said gear or pinion and segment being provided with smooth adjacent bearing-surfaces, and a clutch-connection between said gear wheel or pinion and said shaft for rotating said shaft in one direction only, 105 substantially as herein described.

3. The combination, with the driving-shaft and pulley or wheel thereon, of a rocking frame and hand-lever, and devices, substantially such as described, for rotating said shaft, an internally-ratchet-toothed wheel upon said shaft, and a hand-crank depending from said shaft and having a pawl capable of engagement with said internally-toothed ratchet-wheel, substantially as herein set forth.

4. The combination of the shaft D and pulley D' , and a wheel fast on said shaft and provided with the internal ratchet-teeth, e' , and the gravity-crank G , and gravity-pawl $*$, substantially as herein described.

JOHN G. HOFFMAN.
GEORGE WEBER.
